(57) **CLAIM**

The ornamental design for a sprayer bottle, as shown and described.

DESCRIPTION

FIG. 1 is a perspective view of a sprayer bottle, showing my new design;

FIG. 2 is a right side elevation view thereof;

FIG. 3 is a left side elevation view thereof;

FIG. 4 is a rear elevation view thereof;

FIG. 5 is a front elevation view thereof;

FIG. 6 is a top view thereof;

FIG. 7 is a bottom view thereof; and,

FIG. 8 is a perspective view thereof, shown in environmental use.

The broken lines portions of FIGS. 1-8 show unclaimed subject matter only and form no part of the claimed design.
